ELECTRIC RIVET-FURNACE.

1,078,290.

Specification of Letters Patent. Patented Nov. 11, 1913.

Application filed January 27, 1913. Serial No. 744,522.

To all whom it may concern:

Be it known that we, WILLIAM S. JOHNSON and JOHN W. SHEFFER, residing at Berwick, Columbia county, Pennsylvania, and 5 being citizens of the United States, have invented certain new and useful Improvements in Electric Rivet-Furnaces, of which the following is a full, clear, and exact description, such as will enable others skilled 10 in the art to which it appertains to make and to use the same, reference being had to the accompanying drawings, which illustrate the preferred form of the invention, though it is to be understood that the invention is 15 not limited to the exact details of construction shown and described, as it is obvious that various modifications thereof will occur to persons skilled in the art.

In said drawings: Figure 1 is a front elevation of an electric rivet furnace constructed to disclose a preferred embodiment of our invention. Fig. 2 is a vertical, transverse, sectional view of the same taken on a plane indicated by the line 2—2 of Fig. 1, 20 and looking in the direction of the arrows. Fig. 3 is a plan view looking down upon the device shown in Figs. 1 and 2. Fig. 4 is a side elevation of the device looking from the left-hand side of Fig. 1, and Fig. 5 is a vertical, sectional view showing the link connection with the movable electrode.

Our invention relates to an electric rivet furnace, and it is a primary object of the invention to provide a new and improved 35 furnace in which rivets and similar articles may be quickly and uniformly heated with the least expenditure of electrical energy.

It is a further object of our invention to provide a means whereby metallic members 40 having different cross-sectional areas may be uniformly heated throughout their mass, and a still further object is to provide an electric furnace in which the single act of closing the circuit brings the parts into operative relation to heat the work.

We attain the above objects, broadly, by positioning the rivet head on a stationary electrode of the secondary of a transformer, with the headed end of the rivet inclosed 50 and bring down on the pointed end of the rivet the other electrode of the secondary, thus completing the circuit.

The invention further resides in the construction of a neat, readily transportable

furnace which may be operated by a foot 55 pedal or hand lever, and which may be readily adjusted to accommodate different size rivets.

Described more in detail we have shown a suitable support A, mounted upon which 60 are a pair of vertically spaced horizontally disposed clamping or binding plates B and C, fastened together by long bolts D, disposed between which plates and held thereby is the step-down transformer E, which 65 may be of any conventional form, and is shewn to be of the laminar type, disposed within which and insulated therefrom and from the plates by means of an insulating boxing F, which may be wood, is disposed 70 the leads constituting the primary G, which is in circuit with a suitable source of electric energy H, this circuit being controlled, if desired, by means of a service switch J, but it is to be understood that the operation 75 of the device does not depend upon this service switch, the circuit being completed through the secondary by means hereinafter more fully described.

Disposed in juxtaposition to the primary 80 G and disposed within the boxing F is a relatively long metal strip, preferably of copper, constituting the secondary K. This secondary is suitably held in position and extends above and below the boxing F for 85 some material distance. Extending laterally from the lower portion of the strip K and fastened thereto by means of a bolt 3 is an L-shaped copper plate 4, hereinafter referred to as the stationary electrode, which electrode 90 is insulated from the transformer by means of a sheet of insulating material 5, and is held to the lower plate C by means of a bolt 6, passing through an insulating bushing 7, thereby insulating the stationary electrode 4 95 from the support A.

Resting upon the stationary electrode 4 and abutting the front edge of the sheet 5 and the plates B and C and extending for some distance above the top plate B is the 100 board 8 of insulating material, such as fiber, the front face of which board is recessed to form a dove-tailed vertical groove, which board will hereinafter be referred to as a guide. Slidably mounted within the groove 105 is the upstanding plate 9 of an L-shaped movable electrode 10, the horizontal ledge 11 of which extends parallel with and above

the portion of the stationary electrode 4 in advance of the guide 8. The plate 9 is in the form of a dove-tailed tongue slidably mounted in the groove in the guide 8 and inscribable therein from the upper end thereof. The movable electrode 10 is supported from and electrically connected with the upper end of the secondary K by means of a conductor 13, in this disclosure shown to be an inverted U of laminar metal, preferably of copper strips, having its opposite ends bolted, respectively, to the strip K and plate 9.

Resting upon the portion of the stationary electrode 4 in advance of the guide 8, and spaced from this electrode and positioned beneath the ledge 11 is a receptacle 14 adapted to contain a portion of the rivet, as shown at 15. This receptacle is herein shown to be a rectangular box opened at top and bottom, but it is, of course, to be understood that this receptacle may be cylindrical to accommodate rivets or other members to be heated, or may be divided into a series of compartments to simultaneously heat several articles, if desired. The portion of the stationary electrode below the receptacle 14 has an opening 16 extending therethrough and communicating with the opening 17 in the bottom of the receptacle 14, which opening is tapped to form screw threads. Adapted to be threaded into this opening through the underside of the electrode 4 is an adjustable set screw 18, which set screw may have formed as a part thereof, or, as shown in the drawings, may support the die 19, which die is shown to have a recess 20 formed in its top face. This recess is adapted to substantially fit the contour of the head of the rivet or work to be heated, so that a contact will be made at this point between the stationary electrode and a material extent of the top curved surface of the head of the rivet, it being understood that for bolt or rivet heads of different configurations dies having different shaped co-acting top faces may be substituted, as applicants' object is to afford the maximum area of contact between the electrode and the end of the article to be heated. It is merely necessary to form the die with a contacting face, taking the shape of the negative of the contacting face of the article to be heated, so that should this article, for instance, have a concave end, the die would have a similarly shaped protuberance adapted to fit this concavity. The adjusting screw 18 permits the variation in the position of the bottom of the receptacle relative to its open top, so that the rivet or other article to be heated may project from the receptacle any desired amount, it being understood that the movable electrode 10 is lowered in a manner hereinafter described to contact with the upper end of the rivet to press the same on to the die 19, and to complete the circuit through the secondary and

through the entire length of the article to be heated.

It is a disadvantage at present in heating headed rivets or other articles having a greater mass of material at one portion than another, that the portions of less mass heat more quickly than portions of greater mass, tending, of course, to burn certain portions before the other portions have been heated to riveting or other desired temperatures. A specific object of this disclosure is to obviate this difficulty in the case of heating rivets, and with this in view the heated end is inclosed by the receptacle 14, permitting the pointed end to be exposed, thereby facilitating heat radiation from the pointed end but retarding this radiation from the headed end, which, of course, has the tendency of heating the pointed end more slowly than the headed end.

To protect the operator from sparks or glare, and at the same time to permit him to observe the operation, there is disposed about the ledge 11 and depending therefrom a shield 21 of mica or similar substance, which shield telescopes the outside of the receptacle 14 and the upper portion of the rivet 15.

As shown in the illustration, the device may be operated by a hand lever 22, or a foot pedal 23 arranged in any suitable manner, and for the purpose of this disclosure there is shown supported from the upper plate B a standard 24, pivoted to which intermediate its length is the lever 22, the handle portion of which is conveniently located to the operator and extends rearwardly, and has pivoted to the rear end a depending link 32, the lower end of which is pivoted to the rear end of the pedal lever 33, which lever is fulcrumed at 25 to a depending bracket 26 forming a part of the support A and extending parallel with the lever 22.

The device thus described is connected to the movable electrode by means of a link connection 27 between the electrode and the lever 22. This link connection comprises an inverted U-shaped strap 28, having one leg backed to the plate 9 and the other leg disposed between the front face of the said plate and the adjacent end of the conductor 13, the bolt fastening the conductors also being utilized to fasten this strap. Pivotally mounted in the strap above the plate 9 and positioned in a suitable bearing in the lever 22 is the pivoting pin 30, which pin is insulated from the lever 22 by means of the insulating bushing 31 in said bearing. It will be seen by this construction that manipulating either the levers 22 or 23 will raise and lower the movable electrode from and into contact with the rivet 15, thereby constituting a means for completing the circuit through the secondary and rivet, heat-

ing the rivet or other article to be heated to any desired temperature.

While the device illustrated has been described with some detail, it is, of course, to be understood that applicants are not limiting themselves to the specific embodiment disclosed, but that other means may be devised to accomplish the objects above outlined and more specifically defined in the appended claims.

What we claim is:

1. In an electric furnace for heating rivets, the combination including a heating chamber formed with a bottom forming an electrode and adapted to receive the head of the rivet, and a movable electrode adapted to be brought into engagement with the end of the rivet opposite the head to complete the circuit through the same.
2. In an electric furnace for heating metal articles, in combination an open top heating chamber adapted to contain one end of the article to be heated, said receptacle having an adjustable bottom portion constituting an electrode adapted to contact with said article and vary the proportion of the article within and the portion of the article extending from the receptacle.
3. An electric furnace including a receptacle having a removable and adjustable member therein adapted to support the article to be heated and constituting an electrode, and a second movable electrode adapted to contact with the top of the article.
4. An electric furnace, including a heating chamber adapted to contain a portion of the article to be heated, an adjustable base supporting means for the article to be heated, and electrodes exteriorly of said receptacle one of which is adapted to be brought into electrical contact with said article to complete a heating circuit therethrough.
5. In an electric furnace adapted to heat rivets, an electrode including a heating chamber and a die in said chamber adapted to fit the head of the rivet, whereby a maximum area of contact is afforded between the electrode and the head of the rivet in said chamber.
6. In an electric furnace, a heating chamber, a stationary electrode, an adjustable die carried by said electrode adapted to close the bottom of said chamber and support thereon the article to be heated, and a movable electrode adapted to bear on said article to bring the same in firm engagement with said die and to complete a circuit therethrough.
7. In an electric furnace, an open top receptacle, an electrode in said receptacle adapted to support the article to be heated, a second electrode adapted to be moved into contact with the top of the article, and a protecting screen carried by said movable electrode.

8. In an electric furnace, a vertically disposed guide, an electrode slidably mounted in said guide, a secondary and a flexible conductor electrically connecting said secondary and electrode and supporting said electrode in said guide.

9. In an electric furnace, a vertically disposed guide, an electrode slidably mounted in said guide, a secondary and a flexible conductor electrically connecting said secondary and electrode and supporting said electrode in said guide, and means for actuating said electrode.

10. In an electric furnace, a pair of spaced insulating plates, a transformer held between said plates, a stationary electrode held in insulated position from one of said plates, said electrode electrically connected with the secondary of the transformer, a second electrode electrically connected with said secondary, and means guiding said second electrode in its movement relative to said stationary electrode.

11. In an electric furnace, a secondary in the form of a strip of metal, a lateral extension from one end of said strip adapted to form an electrode, spring conductors affixed to the opposite end of said strip and a movable electrode oppositely disposed to said first mentioned electrode and supported by said conductor.

12. In an electric furnace, a secondary in the form of a strip of metal, a lateral extension from one end of said strip adapted to form an electrode, spring conductors affixed to the opposite end of said strip, a movable electrode oppositely disposed to said first mentioned electrode and supported by said conductor, and a lever controlling said movable electrode.

13. In an electric furnace, a heating chamber, an electrode forming the bottom of said chamber, and an electrode exteriorly of said chamber adapted to have positioned therebetween the article to be heated, said receptacle being adapted to inclose part of the article to be heated and one of the electrodes being movable in operation independently of the article to be heated.

14. In an electric furnace, a heating chamber, in combination with a pair of electrodes adapted to engage opposite ends of an article to be heated, of means adapted to inclose a portion of the article to retard the rate of heat radiation from certain portions thereof, and adjustable means forming part of one of the electrodes adapted to adjust the capacity of the heating chamber.

15. In an electric heating furnace, a pair of electrodes, one of which is movable and one of which is stationary, a heating chamber supported on one electrode, and means in circuit with the stationary electrode adapted to vary the capacity of said heating chamber.

16. In an electric heating furnace, a pair

115

120

125

130

of electrodes, a heating chamber supported by one of said electrodes, and an adjustable member in circuit with said supporting electrode forming the bottom of said chamber and adapted to vary the capacity of said heating chamber.

17. In an electric furnace, a heating chamber, an electrode, an adjustable supporting member connected with the electrode and extending into said heating chamber, and a second and movable electrode adapted to contact with an article positioned in the said chamber.

18. In an electric furnace, a heating chamber, an electrode, an adjustable base supporting member connected with the electrode and extending into said heating chamber, and a second and movable electrode adapted to contact with the top of an article positioned in the said chamber.

19. In an electric furnace, a heating chamber, an electrode, an adjustable base supporting member connected with the electrode and extending into said heating chamber, and a second and movable electrode adapted to contact with the top of an article positioned in the said chamber.

20. In witness whereof we have hereunto set our hands in the presence of two witnesses.

WILLIAM S. JOHNSON.
JOHN W. SHEFFER.
